UNITED STATES PATENT OFFICE.

WILLIAM A. DOBSON, OF BRIDGEPORT, CONNECTICUT, ASSIGNOR TO THE UNDERWOOD ELLIOTT FISHER COMPANY, OF NEW YORK, N. Y., A CORPORATION OF DELAWARE.

TYPEWRITING MACHINE.

Application filed October 20, 1925. Serial No. 63,605

This invention relates to back-spacing mechanism for typewriting machines and more particularly to that class of compact, light portable typewriters where a carriage and platen are case-shifted for upper and lower case typing and the back-spacing mechanism is operated at either case-shift position of the carriage.

In the assembly of a carriage-feeding mechanism the coaction between a tooth of the escapement-wheel with an escapement-dog position establishes a tooth-position for the associated escapement-pinion that varies in different machines due to the variations in a manufactured product and hence the subsequent assembly of a back-spacing mechanism to engage with the teeth of the escapement-wheel or with the teeth of the escapement-pinion requires individual adjustment of a back-space pawl to properly time the engagement of the pawl to a tooth-position and ensure positive coaction thereof from a limited key-action. As these coacting parts are usually carbonized, the pawl frequently requires stoning or grinding, which is impossible in a congested assembly without first removing the pawl. One feature of the present invention provides a carrier for the back-space pawl that has a one-way connection to the back-space key and a single spring-connection to the frame, so that by the simple operation of unhooking one end of the spring, the carrier and its pawl may be easily and quickly removed from the coacting parts and as quickly replaced in operative position. To this end the back-space pawl-carrier is arranged to slip over the free end of the escapement-pinion to rotate upon the faces of the teeth thereof and held in operative relation thereto by a novel arrangement of a spring that both restores the carrier to normal position against a stop and resiliently prevents undue side displacement of the carrier upon the pinion, the latter effect being assisted by the angle of inclination of the assembled pinion. The carrier is further formed with a stop-arm to establish a normal position therefor, a stop for the pawl, and a tension spring for the pawl, all forming a unit of assembly that is removable from the pinion as a unit so that the several stop-members and pawl may be individually fitted to the pre-assembled carriage-feeding devices.

When the carriage-feeding devices and the back-space pawl are assembled upon the case-

shift frame of the carriage, the back-space pawl is usually positively connected by a long link actuated by the back-space key, this positive connection being employed to resist any overthrow of the carriage. In the present invention it is proposed to eliminate the positive connection between the back-space key and the back-space pawl and substitute therefor a one-way or broken connection to the pawl which is effective to back-space the carriage and prevent overthrow thereof by a novel interlocking of the coacting parts. The pawl includes a lateral stud engageable with a long straight face on an upright frame 60 slidable upon the machine-frame at each depression of the back-space key. The stud in shifting with the case-shift frame rides up or down against said arm and a fine, close 65 adjustment of the back-space pawl will be uniformly the same at either case-shift position of the carriage. The key-actuated arm 70 is operative to first swing the pawl into interlocking engagement between two adjacent teeth of the escapement-pinion and the continued movement of said arm causes the carrier, the pawl and the pinion to rotate in unison and any inertia from the carriage-movement will be resisted by the interlock of 75 the pawl backed up by the key-pressed upright arm. 80

All back-spacing mechanisms require some form of a back stop to hold the carriage in its back-spaced position. In the present invention, the stepping dog that normally holds an escapement tooth is so formed as to permit the tooth shifted by the back-space pawl to cam the dog sidewise and subsequently snap under the face of the tooth and thus eliminate a special back stop for this purpose.

A further feature of the invention is to 95 provide a simple, durable, light, compact and inexpensive assembly of the parts to meet the requirements of portable typewriter manufacture.

Other features and advantages will herein- 100
after appear.

In the accompanying drawings,

Figure 1 is a perspective view, in elevation, showing the back-space key operatively connected to the back-space pawl.

Figure 2 is a cross-sectional view, in elevation, through the carriage and the escapement mechanism of an Underwood portable typewriting machine.

Figure 3 is a front view, in elevation, of the 110

escapement mechanism showing the back-spacing pawl in its normal position.

Figure 4 is a plan view of the mechanism illustrated in Figure 3.

Figure 5 is an operational front view, in elevation, of the escapement mechanism, showing the back-spacing pawl swung into engagement with the pinion preparatory to rotating the pinion.

Figure 6 is a view similar to Figure 5, showing the back-space pawl at the end of its throw.

Figure 7 is a view similar to Figure 2, showing the platen in upper-case position, whereas in said Figure 2 it was shown in lower-case position.

Figures 8 and 9 are, respectively, side and plan views of the escapement-wheel, pinion and dogs, showing the passage of a tooth between the dogs under a back-spacing operation.

This invention is applied to an Underwood portable typewriter which has a carriage 10, arranged for letter-space travel upon rails 11 having anti-friction balls 12. Said carriage carries a platen 13 journaled in the end plates of the carriage upon an axle 14 and is urged in one direction by means of a spring-drum 15 around which there is wound a tape 16, the end of which is secured to a stud 17 on the carriage.

In my pending application, Serial No. 63,370, filed October 19, 1925, an escapement mechanism is shown operatively connected to the carriage by means of a rack 19 engaging with a pinion 20 forming an integral part of an escapement-wheel 21, rotatably mounted on a stud 22 fast to a plate 23 which in turn is secured to the back frame 24 of the machine by means of screws 25. The rack is mounted on arms pivoted at the carriage ends and may be disconnected from the pinion in the usual manner.

The escapement disclosed in said application has a pair of dog-rockers 26 and 27 rockably mounted upon a pivot 28, the rockers being vibrated by means of the usual universal bar. Each rocker has a dog 29 and 30 respectively, the dog 30 normally holding some tooth 31 of the escapement-wheel 21 but releasing the tooth 31 when the rocker 26 and its dog 29 are vibrated to intercept the same tooth to initiate a letter-space movement for the carriage.

Sometimes it may be desirable to move the carriage back one space against the tension of the tape 16 which normally urges the carriage to travel in letter-space direction. To this end, there is provided a key 32, near the keyboard of the machine, secured to a key-lever 33, rockably mounted upon a stud 34, which is in turn secured to a side frame 35 by means of a screw 36. The lever 33 is laterally positioned between collars 37 secured to the stud 34, and is guided at the front in a slot

38 cut in a front comb-piece 39, which may also serve as a re-enforcing element between the side frames of the machine, to which it is secured by means of screws 40. Since the location of the key 32, in the keyboard, is subservient to the convenience of the operative, and since the location of the escapement-pinion 20, upon which a back-space pawl 41 rotates, is also predetermined in view of the design of the carriage, linkage must be provided for operatively connecting said key to said pawl. In the present invention, the linkage comprises a rear extension 42 of said lever 33, upon which there is pivotally mounted a link 43 by means of a stud 44. Said link 43 extends rearwardly and is connected, by means of a screw 45, to a bell-crank 46, pivotally mounted upon a shoulder stud 47 secured to a bracket 48 which in turn is secured to the side frame 35 by means of screws 49. The bell-crank has a rearwardly-extending arm 50 and carries a link 51 pivotally mounted at 52, which link extends toward the center of the machine and terminates with an upwardly-extending arm 53 designed to engage a stud 69 carried by said pawl. By depressing the key 32, the link 51 is caused to slide on a guide 54, which engages within an elongated slot 55 in said link. The guide is secured to a bracket 56, which is in turn secured to a cross-rail 57 by means of screws 58, the cross-rail being fast to the side frame 35 by means of screws 59.

Upon depressing the key 32, the link 51 will be slid from a position shown in Figure 3 to that shown in Figure 5, thereby swinging the pawl 41 into engagement with the pinion 20. Said pawl 41 is pivotally mounted upon a stud 60, secured to a plate or carrier 61 which in turn is pivotally mounted over the teeth of the pinion 20. The carrier is held in normal position, as shown in Figures 3 and 5, by means of a spring 62 actuating between a forwardly-extending tab 63 of the plate 23 and an extension 64 of the carrier 61. Said extension 64 serves also as a means for positioning the carrier 61, which is held against a stop 65 forming an integral part of the plate 23. Since the pawl is normally held out of engagement with the pinion 20 by a spring 66, which is lighter than the spring 62 holding the carrier 61 in its normal position, it will be seen that, upon sliding the link 51, the pawl will be first swung into engagement with the teeth of the pinion, and then the carrier will be swung with the pinion. In order that the pawl may be normally held away from the pinion, the same may be provided with an extension 67, held against a stop 68 forming an integral part of the carrier 61.

In the particular type of case-shift machine with which this invention is illustrated, the escapement mechanism is raised as a unit when the platen is elevated to receive typing

in upper case, whereas the link 51 and all allied linkage, including the back-space key, are operatively mounted upon the machine frame. It will be readily understood, therefore, that mechanism must be provided to connect the link 51 and the pawl 41 in a manner to permit an up-and-down movement of the pawl, while maintaining operating relationship between the pawl and the link. To this end, the arm 53 of said link 51 is made long enough to engage the stud 69 in both positions of the carriage shift, as shown in Figures 2 and 7.

It will be noted that, owing to the manner in which the escapement mechanism operates, it is possible to rotate the escapement-wheel 21 backwardly, said escapement-wheel having backed-off teeth at 70 on the side of the wheel 21, which teeth engage with the beveled under face of the stepping dog 30 held in engagement with the teeth by means of a spring 71.

The key-lever 33 and its associated linkage are held in their normal position by means of a spring 72, having one end secured to a downwardly-extending arm 73 forming an integral part of said key-lever, the other end being secured to a spring-stud 74 fast to a lug 75, extending inwardly from the side frame 35.

It will be noted that the escapement-pinion 20 is open on the forward end, permitting the carrier 61 and its back-space pawl 41 to be adjusted over the end thereof to rotate upon the teeth of the pinion, and that the pinion rotates within the assembled carrier in letter-spacing; that the carrier is held in operative position upon the pinion by the tension of a spring 62; that the carrier, with the pawl 41 and its spring 66 assembled thereto, may be removed from the pinion after first unhooking one end of the spring 62, thus enabling the assembler to quickly and individually adjust the extension 67 to the stop 68, adjust the extension 64 to the stop 65, adjust the tension of the spring 66 or adjust the tooth of the pawl 41 to the teeth of the pinion by stoning or grinding, all adjustments that would be difficult to make if these parts were permanently assembled to the carriage-frame; and that the back-spacing unit has no positive, pivotal connection to the key-actuated link, to interfere with the removal or assembly of the unit or interfere with the case-shifting movement of the unit with the carriage.

Variations may be resorted to within the scope of the invention, and portions of the improvements may be used without others.

Having thus described my invention, I claim:

1. The combination with a typewriting machine having a carriage arranged for letter-space travel, a carriage-feeding mechanism therefor, and a pinion-and-rack ar-

rangement for operatively connecting the carriage and the carriage-feeding mechanism, of means for back-spacing the carriage, said means including a depressible key near the keyboard of the machine, a carrier rotatably mounted upon the pinion, a normally-inoperative pawl mounted upon the carrier and arranged to first engage said pinion and then rotate with the pinion in a direction opposite to the letter-space rotation of the carriage, and means actuated by said key and operatively connecting said pawl.

2. The combination with a typewriting machine having a case-shiftable carriage arranged for letter-space travel, a carriage-feeding mechanism therefor, and a pinion-and-rack arrangement for operatively connecting the carriage and the carriage-feeding mechanism, of means controlled by a key and shiftable with the carriage for back-spacing the carriage, said means including a carrier rotatably mounted upon the pinion, a normally-inoperative pawl pivotally mounted upon said carrier and means on the frame and actuated by said key for engaging the pawl with the teeth of said pinion and then rotating with the pinion at either case-shift position of the carriage.

3. The combination with a typewriting machine having a carriage arranged for letter-space travel upon a case-shift carriage-frame, and a carriage-feeding mechanism mounted upon said shift-frame and operatively connected to said carriage to control the step-by-step movement thereof, said carriage-feeding mechanism including a pinion on the case-shift frame and a rack on said carriage meshing with said pinion, of pinion-rotating means wholly mounted upon the case-shift frame for back-spacing the carriage, said means including a carrier and a pawl jointly operative to effect a backward rotation of the pinion, and key-actuated mechanism having a one-way connection operative to engage the pawl at either case-shift position of the carriage.

4. The combination with a typewriting machine including a case-shift frame, a carriage arranged for letter-space travel thereupon, and a carriage-feeding mechanism operatively connected to said carriage to control the step-by-step movement thereof, said carriage-feeding mechanism including a pinion on the case-shift frame and a rack on said carriage meshing with said pinion, of means for back-spacing the carriage, said means including a carrier and a pawl mounted upon said pinion and cooperating to rotate the pinion in a reverse direction by first rotating about the pinion and then rotating with the pinion to back-space the carriage.

5. The combination with a typewriting machine including a case-shift frame, a carriage arranged for letter-space travel thereupon, and a carriage-feeding mechanism operatively

- connected to said carriage to control the step-by-step movement thereof, said carriage-feeding mechanism including a pinion on the case-shift frame and a rack on said carriage meshing with said pinion, of means for back-spacing the carriage, said means including a carrier rotatable upon the pinion, a pawl on the carrier co-operating with said pinion, and a linkage operatively connecting said pawl, said linkage including a sliding member operatively connected to said pawl, a bell-crank operatively connected to said sliding member and a link operatively connecting said bell-crank, and a key to actuate said linkage.
15. 6. The combination with a typewriting machine having a carriage arranged for longitudinal travel upon a case-shiftable frame, an escapement mechanism to letter-space the carriage in one direction, and a back-spacing mechanism to letter-space the carriage in a reverse direction, both mechanisms being mounted upon the shiftable carriage-frame, of means for actuating the back-spacing mechanism at either case-shift position thereof, including a key and a link, said link being relatively fixed to the machine frame and actuated by the key, said link having a long driving face engageable with a part of the back-spacing mechanism to compensate for the rise and fall of said back-spacing mechanism in case-shifting.
20. 7. The combination with a typewriting machine having a case-shiftable carriage and means for controlling the letter-space movement thereof, said means including a pinion-and-rack arrangement, of means actuated by a key for back-spacing the carriage one space at each key depression, said back-spacing means including a carrier rotatably mounted upon the pinion, a pawl pivotally mounted upon said carrier to engage the teeth of the pinion, means for normally holding the pawl away from the teeth of said pinion, and means operatively connecting said pawl with said key to afford a one-way engagement with the pawl, to render the pawl operative at either case-shift position of the carriage.
25. 8. The combination with a typewriting machine having a carriage and means for controlling the letter-space movement thereof, said means including a pinion-and-rack arrangement, of means actuated by a depressible key for back-spacing the carriage one space at each key depression, said last-mentioned means including a pawl pivotally mounted upon a plate, means for normally holding the pawl away from the teeth of said pinion, means operatively connecting said pawl with said key in a manner to afford the engagement of the pawl with the teeth of the pinion so as to rotate the pinion one space, backwardly, when the key is depressed, and means for resiliently holding said plate in a predetermined position, said last-mentioned means including a stop-device co-operating

with a projection forming an integral part of said plate, a spring secured to said projection, and fixed means for holding the spring under tension.

9. The combination with a typewriting machine having a carriage and means for controlling the letter-space movement thereof, said means including a pinion-and-rack arrangement, of means actuated by a key for back-spacing the carriage one space at each key depression, said last-mentioned means including a carrier mounted upon the pinion and a pawl pivotally mounted upon said carrier to swing around or with said pinion, means for normally holding the pawl away from the teeth of said pinion, and means operatively connecting said pawl with said key in a manner to afford the engagement of the pawl with the teeth of the pinion so as to rotate the pinion one space, said connecting means including a key-actuated sliding member formed with an upright extension operative for a one-way connection to actuate the pawl.

10. The combination with a typewriting machine having a carriage and means for controlling the letter-space movement thereof, said means including a pinion-and-rack arrangement, of means actuated by a depressible key for back-spacing the carriage one space at each key depression, said last-mentioned means including a pawl pivotally mounted upon a plate, means for normally holding the pawl away from the teeth of said pinion, means operatively connecting said pawl with said key in a manner to afford the engagement of the pawl with the teeth of the pinion so as to rotate the pinion one space, backwardly, when the key is depressed, said connecting means including a rockably mounted key-lever operated by said key, a link operatively connecting a rear extension of said lever to a bell-crank in a manner to draw on the link and swing the bell-crank when the key is depressed, and means for operatively connecting said bell-crank to said pawl, said last-mentioned means including a slidably mounted link, a bracket for supporting the link, said link having an elongated slot designed to engage with a stud secured to said bracket, and a tab forming an integral part of said link and engaging with a pin fast to the pawl.

11. The combination with a typewriting machine having a shiftable carriage and an escapement mechanism therefor, said mechanism including a pinion-and-rack arrangement designed to be shifted with the carriage, of means for back-spacing the carriage, said means including a carrier rotatably mounted on said pinion, means for resiliently positioning said carrier, a pawl pivotally mounted on said carrier, means for resiliently holding the pawl out of engagement with the teeth of said pinion, a sliding member, means for op-

eratively connecting said pawl with the sliding member, and a key operatively connected to actuate the sliding member.

12. The combination with a typewriting machine having a shiftable carriage and an escapement mechanism therefor, said mechanism including a pinion-and-rack arrangement designed to be shifted with the carriage, of means for back-spacing the carriage, said 5 means including a carrier rotatably mounted on said pinion, means for resiliently positioning said carrier, a pawl pivotally mounted on said carrier, means for resiliently holding the pawl out of engagement with the teeth 10 of said pinion, a sliding member, means for operatively connecting said pawl with the sliding member, said sliding member being operatively connected to a key, said last-mentioned connections including a key-lever 15 rockably mounted on a stud fast to the side frame of the machine, means for laterally positioning said key-lever and for resiliently holding it in its normal position, a rearwardly-extending arm on said lever, and means 20 for moving said sliding member in a manner to afford the rocking of the pawl to engage with the teeth of the pinion and to swing the carrier on which the pawl is mounted so as to rotate the pinion therewith.
- 25 13. The combination with a typewriting machine having a case-shiftable carriage and an escapement-mechanism therefor, said mechanism including a pinion-and-rack arrangement designed to be shifted with the carriage, of means for back-spacing the carriage, said means including a carrier rotatably mounted upon said pinion, means for yieldingly positioning said carrier, a pawl pivotally mounted on said carrier, means for 30 holding the pawl out of engagement with the teeth of said pinion, a sliding member, means operatively connecting said pawl with the sliding member, said sliding member being operatively connected to a key-lever rock- 35 ably mounted on a stud fast to the side frame of the machine, means for laterally positioning said key-lever and for yieldingly holding it in its normal position, a rearwardly-extending arm on said lever, and means for 40 connecting said arm with said sliding member to effect the rocking of the pawl to engage with the teeth of the pinion and then swing the carrier and the pawl to rotate the pinion therewith, said sliding member in- 45 cluding an upright arm forming an integral part thereof, and a stud on said pawl engaging with said arm, whereby a one-way connection is effected between the arm and the stud regardless of the case-shift position of the 50 carriage.
- 55 14. The combination with a typewriting machine having a traveling carriage provided with a letter-space feeding mechanism including a rack and a pinion, of an annular

rotatable back-spacing unit on the periphery 65 of the pinion and having means co-operative therewith to effect a reverse feed of the carriage when rotated, and means yieldingly retaining said unit on said pinion.

15. The combination with a typewriting machine having a traveling carriage provided with a letter-space feeding mechanism including a rack and a pinion, of an annular rotatable back-spacing unit on the periphery 70 of the pinion and having means co-operative therewith to effect a reverse feed of the carriage when rotated, means yieldingly retaining said unit on said pinion, and key-actuated means on the frame operatively connected to 75 rotate said unit.

16. The combination with a typewriting machine having a traveling carriage provided with a letter-space feeding mechanism including a rack and a pinion, of an annular rotatable back-spacing unit on the periphery 80 of the pinion and having means co-operative therewith to effect a reverse feed of the carriage when rotated, a spring operative to yieldingly retain said unit on said pinion and restore said unit to a normal position, and 85 key-actuated means slidable on the frame and operative to rotate said unit in a back-spacing direction against the tension of said spring.

17. The combination with a typewriting machine having a traveling carriage provided with a letter-space feeding mechanism including a rack and a pinion, of an annular rotatable back-spacing unit to rotate upon the periphery of the pinion and having means 90 co-operative with the pinion to effect a reverse feed of the carriage, and a spring operative to yieldingly position the unit upon the pinion.

18. The combination with a typewriting machine having a traveling carriage provided with a letter-space feeding mechanism including a rack and a pinion, of an annular rotatable back-spacing unit including a carrier to rotate upon the periphery of the pinion 95 and having a pawl engageable with the pinion to effect a reverse feed of the carriage, and a restoring spring connected to the carrier that is also operative to yieldingly position the carrier upon the pinion.

19. The combination with a typewriting machine having a letter-space feeding mechanism including a rack and a pinion, of a back-spacing unit assembled upon the pinion including a carrier rotatable upon the pinion, and a pawl rotatable with the carrier and co-operative with the pinion to effect a reverse feed of the carriage.

20. The combination with a typewriting machine having a case-shiftable traveling carriage provided with a letter-space feeding mechanism including a rack and a pinion, of a back-spacing unit assembled to rotate upon the pinion and having means co-operative

therewith to effect a reverse feed of the carriage upon rotation of the unit, and key-actuated means on the frame disconnected from the unit that is operative to actuate the unit at either case-shift position of the carriage.

21. The combination with a typewriting machine having a case-shiftable traveling carriage provided with a letter-space feeding mechanism including a rack and a pinion, of a back-spacing unit assembled to rotate upon the pinion and having means co-operative therewith to effect a reverse feed of the carriage upon rotation of the unit, and an actuator on the frame having a vertical-edge contact with one part of the unit and operative

to uniformly vibrate the unit at either case-shift position of the carriage.

22. The combination with a typewriting machine having a case-shiftable traveling carriage provided with a letter-space feeding mechanism including a rack and a pinion, of a back-spacing unit assembled to rotate upon the pinion and having means co-operative therewith to effect a reverse feed of the carriage upon rotation of the unit, and a key-actuated slide on the frame having an upright extension operative to abut and vibrate the same part of the unit at different case-shift positions of the carriage.

WILLIAM A. DOBSON.
